CLAIM

The ornamental design for a charging base for a cordless telephone, as shown and described.

DESCRIPTION

FIG. 1 is a front, top, and left side perspective view of a charging base for a cordless telephone showing our new design;

FIG. 2 is a right side elevational view thereof;

FIG. 3 is a rear elevational view thereof;

FIG. 4 is a bottom plan view thereof; and,

FIG. 5 is a front, top, and left side perspective view of a second embodiment of that shown in FIG. 1 wherein the only difference is in the enlargement of the inset plate at the top right.

The broken lines shown in FIGS. 1-5 are for illustrative purposes only and form no part of the claimed design.

FIG. 1***FIG. 2***E 2

FIG. 3FIG. 4

FIG. 5
